DAMPENING DEVICE FOR PRINTING MACHINES

Anton Stobb, Long Island City, N. Y., assignor to
R. Hoe & Co., Inc., New York, N. Y., a corporation of New York

Application August 26, 1935, Serial No. 37,987

16 Claims. (Cl. 101—148)

This invention relates to moistening or dampening devices and more particularly to improved dampening rollers for use in lithographic or planographic printing machines, and to improved means for supplying suitable moistening fluid to the rollers.

In lithographic printing, plates of zinc or other suitable material are employed, and on these plates images are transferred from drawings or engravings by a process which results in the existence of water-repellent surfaces coextensive with the matter to be printed. Where such plates are used, printers employ a process in which dampening fluid is supplied to the plates, and this fluid will adhere to the plates at all points except where the images having the water-repellent exists. After subjecting the plates to moisture, the plates are inked and the ink will adhere to the moisture-repellent portions of the surfaces of the plates, but not to those portions which have been moistened. As understood by those skilled in the art, it is desirable and essential that an accurately controlled quantity of suitable ink-repellent moistening fluid, preferably an aqueous acid solution, be supplied to the planographic printing plate in the form of a uniform fluid film. Various means and mechanism have heretofore been employed in attempts to apply a uniform film of water, or suitable ink-repellent fluid, to the printing surface of planographic printing plates in accurately controlled quantities, but, in most instances, much difficulty is experienced in applying a uniform film of the dampening solution to the surface of the printing plate, therefore an object of this invention is to provide improved instrumentalities for supplying an accurately controlled quantity of suitable ink-repellent dampening fluid to the printing surface of planographic printing plates in the form of a uniform fluid film.

Another object of the invention is to provide a moistening or dampening roller for use in lithographic printing machines, and means for supplying a suitable ink-repellent fluid from a remote fountain through a conduit and into the interior of the roller and then to the peripheral surface of the roller.

A more specific object of my present invention is to provide a cylindrical dampening or moistening roller for use in lithographic printing machines, the roller being rotatably mounted on a movable or rockable tubular shaft which extends axially through the roller and communicates with a fountain in which a constant level of suitable ink-repellent dampening fluid or solution is

maintained, thereby maintaining a constant fluid level in the tubular shaft so that a rocking or oscillatory movement of the shaft of predetermined amplitude discharges a predetermined quantity of the dampening fluid into the dampening roller.

A further object of my invention is to provide an improved dampening or moistening roller for use in lithographic printing machines, the roller being rotatably supported by a movable tubular shaft or conduit which communicates with a fountain containing a suitable ink-repellent dampening fluid, and the fountain being constructed and arranged to maintain a constant fluid level in the tubular shaft, the tubular shaft being driven by an operating component of the printing machine to thereby discharge a quantity of dampening fluid from the tubular shaft into the interior of the dampening roller, and there being provided manually operable instrumentalities under control of an operator for varying the amplitude of movement imparted to the tubular shaft to thereby vary the quantity of fluid discharged from the tubular shaft or conduit into the moistening roller.

It is also an object of this invention to provide a dampening roller for use in lithographic printing machines, and fluid supply means therefor, of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detailed description of an improved dampening roller and dampening fluid supplying means therefor for use in lithographic printing machines will now be given in connection with the accompanying drawings forming a part of the specification, wherein:

Figure 1 is a fragmental vertical sectional view taken axially through the improved dampening roller and through the machine frame, dampening fluid fountain and reservoir;

Figure 2 is a vertical fragmental sectional view

taken on the line 2—2 of Figure 1 and looking in the direction indicated by the arrows;

Figure 3 is a similar view, but showing the fountain and reservoir components in different operative positions;

Figure 4 is a horizontal fragmental sectional view taken on the line 4—4 of Figure 1 and looking in the direction of the arrows;

Figure 5 is a detailed vertical sectional view taken on the line 5—5 of Figure 3 and looking in the direction indicated by the arrow; and

Figure 6 is a fragmental plan view depicting the improved variable leverage drive means for the tubular shaft or conduit, the view looking in the direction of the arrow 6 indicated in Figure 2.

Referring to the drawings, in which similar reference characters designate corresponding parts, there is shown the side members 10 and 11 of a planographic printing machine frame, and the side member 11 has an aperture 12 formed therein for the reception of a bearing bushing 13 in which a conduit or tubular shaft 15 is rotatably mounted. The end of the conduit 15 which is mounted in the bushing 13 has a plug or stop member 16 suitably secured therein, and a thrust ring 17 is secured to the tubular shaft or conduit 15 by a set screw or other suitable securing device indicated at 18, thereby preventing longitudinal movement of the conduit 15 in a direction towards the end member 11 of the machine frame. An aperture 20 is formed in the side member 10 of the machine frame in axial alignment with the aperture 12 of the frame member 11, and a bearing bushing 21 is positioned within the aperture 20 to rotatably support the tubular shaft or conduit 15. The bearing bushing 21 extends axially from a sleeve 22 of a stuffing box or gland, and the sleeve is received in an enlarged aperture 23 formed in the side member 10 of the machine frame, and an annular shoulder 25 is formed between the aperture 20 and enlarged aperture 23 and against this annular shoulder a suitable packing material 26 is thrust by the beveled outer terminal 27 of the sleeve 22 to provide a fluid-tight joint around the bearing bushing 21. An annular flange 28 extends radially from the sleeve 22, and the outer terminal of the flange 28 is cut away to define an annular shoulder 30 which is engaged by an annular rib or flange 31 formed on a retaining ring or member 32 which is secured to the frame member 10 by means of bolts or other suitable securing devices indicated at 33, thereby forcing the tubular sleeve 22 inwardly so that its beveled terminal 27 is thrust against the packing material 26, thus securing the tubular sleeve 22 and bearing bushing 21 in the frame member 10 and providing a water-tight joint around the bearing bushing 21. The sleeve 22 of the stuffing box or gland has a recess 35 formed therein for the reception of suitable packing material 36 which is packed tightly around the outer surface of the conduit or tubular shaft 15 by a tubular nut or securing member 37 that is threaded into the sleeve 22, as indicated at 38, thereby forming a water-tight joint within the sleeve 22 around the tubular shaft or conduit 15 but permitting rotation or rocking movement of the tubular shaft.

70 A casing or housing 40 is secured to the outer surface of the machine frame side member 10 by bolts or other suitable securing devices 41, and this housing has an upper compartment providing a reservoir 42 for the reception of a suitable dampening fluid to be employed in dampen-

ing the planographic printing plate of the lithographic printing machine. Inasmuch as the construction of lithographic printing machines is well understood by those skilled in the art, only the components of the printing machine which form elements of this invention are here illustrated. A water tight partition 43 extends horizontally across the housing 40 to provide a bottom for the reservoir 42 and the top of a fountain 45 formed in the housing 40 immediately below the reservoir 10 42, and an aperture 46 is formed in the reservoir housing in order to communicate the fountain 45 with the aperture 20 formed in the machine frame side member 10. The housing 40 is secured to the machine frame member 10 by the 15 bolts or screws 41, so that a water-tight joint is provided between the housing 40 and the machine frame member 10 around the fountain aperture 46, and this water tight joint may be secured to the machine frame member 10 by the 20 bolts or screws 41, so that a water-tight joint is provided between the housing 40 and the machine frame member 10 around the fountain aperture 46, and this water tight joint may be produced by machining the abutting surfaces of 25 the machine frame 10 and the fountain housing 40, or, if desired, a gasket of suitable material may be interposed between the machine frame member 10 and the housing 40, but inasmuch as the employment of water-tight gaskets is old and 30 well understood in the art, the gasket is not here illustrated. A removable cover member 46 is secured to the reservoir 42 to form the top thereof, and this cover 46 may be removed to supply 35 dampening fluid to the reservoir, or, if preferred, the fluid may be pumped or otherwise supplied into the reservoir through a suitable conduit from a distant supply source or storage tank. Inasmuch as the employment of instrumentalities for supplying fluid to a reservoir or tank is 40 well understood by those skilled in the art, such device is not illustrated. In order to maintain a constant or predetermined fluid level within the fountain 45, suitable control instrumentalities are provided and include a float 47 carried by 45 spaced arms 48 that extend from one side of a shaft or supporting member 50 which is pivotally secured within the fountain by screws or other suitable securing devices 51. The screws 51 extend through bearing bosses 52 formed in the shaft 50, thereby pivotally supporting the shaft 50 so that the float 47 may move about the securing members 51 at its pivot or fulcrum point. A finger 53 extends from one side of the shaft 50 50 in a direction away from the float 47 and is positioned to engage the lower rounded terminal of a threaded valve stem or screw 55 which is threaded through a frusto conical valve 56, and this screw has a manipulating wing or head 57 55 formed at its upper terminal. The conical surface of the valve 56 engages the conical surface 58 of a soft or yieldable tubular valve seat 60 received within a cylindrical recess 61 formed in the partition member 43, and an outlet aperture 62 is formed in the partition 43 at the bottom of the recess 61. Although the valve seat member 60 is preferably formed of rubber or other yieldable material, it may also be formed of fiber, metal or other hard material, in which 65 event, the conical surfaces of the valve seat member 60 and the valve 56 are formed to accurately interfit. Any suitable means may be provided for draining the dampening fluid from the fountain 45, and, in the present instance, a 70 manually operable drain valve or cock 63 is secured to the lower terminal of the fountain 45, thereby permitting the dampening fluid to be conveniently drained from the fountain.

Spaced antifriction bearings 65 are mounted 75

on the tubular shaft or conduit 15, and a tubular member 66 forming the inner cylindrical shell of an improved composite dampening roller is mounted for rotation on the antifriction bearings 65. Annular members or rings 67 are secured at the opposed terminals of the inner cylindrical shell 66 to provide fluid-tight joints between the inner surface of the tubular member or cylindrical shell 66 and the outer surface of the tubular shaft or conduit 15 to prevent the escape of the dampening fluid past the antifriction bearings. The tubular member or cylindrical shell 66 is provided with a plurality of perforations 68, preferably at its intermediate portion, and a sleeve 70 formed of felt or other suitable soft porous material surrounds the perforated portion of the cylindrical shell 66. An outer tubular member or cylindrical shell 71 surrounds the felt sleeve 70 and is provided with a plurality of perforations 72, preferably aligned with the perforations 68 of the inner cylindrical shell 66, although the alignment of the apertures 68 and 72 is not essential. The outer cylindrical shell 71 is surrounded by a soft porous tubular member or covering 73, preferably formed of molleton or other cotton fabric, and the opposed terminals 75 of the tubular soft covering 73 are secured to annular members or clamp rings 76 by screws or other suitable securing devices indicated at 77. The outer surface of each clamp ring 76 is threadedly secured to the threaded inner surface 78 of the outer perforated cylindrical shell 71, and the inner surface of each clamp ring 76 engages an annular shoulder 80 formed on the outer surface of the inner cylindrical shell 66, thereby rigidly securing the outer cylindrical shell 71 to the inner cylindrical shell 66 and also securing the felt sleeve 70 and molleton covering 73 in position. A thrust ring 81 engages the antifriction bearings at one end of the inner cylindrical shell 66, and this thrust ring is secured to the conduit or tubular shaft 15 by means of a set screw or other suitable securing device 82, thereby preventing longitudinal movement of the composite dampening roller towards the frame side member 11. Axial or longitudinal movement of the composite dampening roller in a direction towards the frame side member 10 is prevented by means of a split hub or sleeve 83, to be herein-after more fully disclosed.

In order to rock or oscillate the tubular shaft or conduit 15 about its axis, means are provided for operably connecting the tubular shaft 15 with an operating component of the printing machine, and, to this end, the split hub or sleeve 83 is rigidly clamped to the tubular member 15 by suitable clamping members or screws 84, best shown in Figures 2 and 3 of the drawings. An arm 85 is formed integral with and extends radially from the split hub 83, and the outer terminal of this arm is pivotally secured to spaced links or straps 86, as indicated at 87. The opposed terminals of the links 86 are pivotally secured, as indicated at 88, to a block 90 which is mounted for sliding movement in a rectangular recess 91 formed in a lever member 92 which is fulcrumed on a stud 93, as indicated at 94, and the stud 92 extends inwardly from and is secured to the machine frame member 10, the securing devices being indicated at 95. The block 90 has an axially-extending threaded aperture 96 formed therein for the reception of a threaded rod or screw 97 which extends longitudinally of the rectangular recess 91, and the opposed ends 75 of the screw 97 have unthreaded cylindrical por-

tions which are mounted for rotation in the lever member 92, as indicated at 98. A manipulating head or knob 99 is secured to one terminal of the screw 97 by a pin or other suitable securing device indicated at 100. The inner terminal of this knob 99 rests against the end of the lever member 92 to prevent inward longitudinal or axial movement of the screw 97 relative to the lever 92, and the opposed terminal of the screw 97 has a collar or washer 101 mounted thereon and secured in position by means of a pin or other suitable securing device 102. A helical extension spring 103 is interposed between the washer 101 and the end of the lever 92, thereby maintaining the screw 97 in correct longitudinal position and also aiding in preventing the free rotation of the screw 97. In order to impart movement to the lever 92, an operating component of the printing machine is operably connected therewith, and, in the exemplary form illustrated, a driven shaft 105 of the printing machine is mounted for rotation in the bearings 106 supported by the machine frame member 10, and the outer terminal of the shaft 105 is provided with an offset or eccentric stud 107 pivotally secured to a terminal of a link 108. The opposed terminal of the link 108 is bifurcated to provide spaced straps 110, and these straps straddle and are pivotally secured to the lever 92, as indicated at 111.

The tubular shaft or conduit 15 has outlet apertures 19 formed therein to permit the discharge of fluid from the conduit 15 into the dampening roller when the conduit or tubular shaft 15 is rocked, as will be hereinafter more fully disclosed, and, in the present instance, a longitudinal row of the apertures 19 is provided, as best shown in Figures 2 and 3, although it is to be understood that any preferred number or disposition of the apertures may be resorted to. The location of these apertures is chosen with relation to the fluid level maintained within the conduit 15, so that controlled quantities of fluid may be discharged from the conduit 15 into the composite dampening roller.

In operation, a predetermined fluid level is maintained within the fountain 45 by employing the float 47, which rises and falls with the fluid level, and the height of fluid level may be controlled by adjusting the threaded valve stem 55 by rotating its manipulating head 57, thus causing the stem 55 to rotate relative to the valve 56 to thereby cause the lower terminal of the stem to project the desired distance below the valve. When the fluid drops to the selected level the finger 53 engages the valve stem 55 and unseats the valve 56, thus admitting fluid from the reservoir 42 into the fountain 45 to again establish the desired fluid level. The fluid level is chosen with relation to the conduit 15 so that there is always some fluid present in the conduit. The operation of the printing machine rotates the shaft 105, which, in turn, moves the lever 92 about its fulcrum stud 93 through the interposed link 108, and the movement of the lever 92 transmits rocking or oscillatory movement to the conduit 15 through the interposed links 86 and arm 85. As the arm 85 moves upwardly the apertures 19 of the conduit 15 are moved below the fluid level within the conduit 15, thus causing the fluid to be discharged from the conduit into the tubular shell 66 of the composite dampening roller. The quantity of fluid discharged from the conduit 15 into the tubular shell 66 of the composite dampening roller is controlled by the position of the

sliding block 90 in the lever 92, and when an operator manipulates the knob 99 to move the block outwardly away from the fulcrum point of the lever 92, an oscillatory or rocking movement of great amplitude is imparted to the conduit 15, thus causing the apertures 19 of this conduit to remain a longer period of time below the fluid level and consequently discharge a relatively greater quantity of fluid into the dampening roller. If a smaller quantity of fluid is to be discharged, the operator manipulates the knob 99 to move the sliding block 90 towards the fulcrum point of the lever 92, thus reducing the amplitude of the rocking or oscillatory motion of the conduit 15, which results in the discharge of a relatively smaller quantity of fluid into the dampening roller during each operative impulse of the conduit 15.

After the desired quantity of dampening fluid has been discharged from the conduit 15 through the apertures 19 into the tubular shell 66 of the dampening roller, this fluid then, owing to the centrifugal action of the roller, passes through the perforations 68 of the tubular shell 66 into the felt sleeve 70 and then through the perforations 72 of the outer cylindrical shell 71 into the outer molleton covering 73, and from this point the dampening fluid is distributed through the usual rollers, not shown, to the planographic printing plate in conformity with the usual practice which is well understood by those skilled in the art. When the printing machine is not in operation, the apertures 19 of the conduit are positioned above the fluid level of the fountain 45 and conduit 15, thus preventing the discharge of the fluid through the apertures 19 into the dampening roller.

Having thus described my invention what I claim is:

40 1. In a dampening device for printing machines, a fountain for dampening fluid, a dampening roller mounted for rotation, a movable conduit having outlet apertures and extending from and communicating with the fountain to convey fluid from the fountain towards the roller, driven means for imparting such movement to the movable conduit as to discharge the fluid from the conduit through the outlet apertures to the roller.

2. In a dampening device for printing machines, a fountain for dampening fluid, a dampening roller mounted for rotation, a movable conduit extending axially through the roller and having outlet apertures located within the roller, the conduit communicating with the fountain to convey fluid from the fountain into the portion of the conduit which is located within the roller, driven means for imparting such variable movement to the conduit as to discharge variable quantities of fluid from the conduit through the outlet apertures into the roller, and means for permitting the passage of the fluid from the interior of the roller to its exterior.

3. In a dampening device for printing machines, a fountain for dampening fluid, a dampening roller mounted for rotation, a rotatable conduit having outlet apertures and extending from and communicating with the fountain to convey fluid from the fountain towards the roller, driven means for imparting rotary movement of variable amplitude to the conduit whereby the said outlet apertures of the conduit are moved relative to the fluid level in the conduit to discharge variable quantities of fluid from the conduit to the roller commensurate with the amplitude of rotary movement of the conduit.

4. In a dampening device for printing machines, a fountain for dampening fluid, means for maintaining a constant fluid level in the fountain, a dampening roller mounted for rotation, a movable conduit having apertures formed therein and extending from the fountain, the conduit communicating with the fountain to convey fluid from the fountain to the roller, driven means for imparting movement to the conduit whereby the conduit apertures are moved from a point above the fluid level to a point below the fluid level thereby discharging fluid from the conduit to the roller.

5. In a dampening device for printing machines, a fountain for dampening fluid, means for maintaining a constant fluid level in the fountain, a dampening roller mounted for rotation, a movable conduit having apertures formed therein, the conduit extending from and communicating with the fountain to convey fluid from the fountain to the roller, driven means for imparting variable movement to the conduit whereby the conduit apertures are moved from the point above the fluid level through variable paths of travel to points below the fluid level thereby discharging variable quantities of fluid to the roller.

6. In a dampening device for printing machines, a fountain for dampening fluid, a dampening roller mounted for rotation, a conduit extending axially through the roller and having outlet apertures located within the roller, the conduit communicating with the fountain to convey fluid from the fountain into the portion of the conduit which is located within the roller, the conduit being mounted for rocking movement, driven means for imparting rocking movement of variable amplitude to the conduit whereby the said outlet apertures are moved relative to the fluid level in the conduit to discharge variable quantities of fluid from the conduit into the roller, and means for permitting the passage of fluid from the interior of the roller to its exterior.

7. In a dampening device for printing machines, a fountain for dampening fluid, a dampening roller mounted for rotation, a rockable conduit having apertures formed therein and extending from and communicating with the fountain to convey fluid from the fountain to the roller, driven means for imparting rocking movement of variable amplitude to the conduit thereby moving the conduit apertures from points above the fluid level to points below the fluid level whereby variable quantities of fluid are discharged from the conduit to the roller.

8. In a dampening device for printing machines, a fountain for dampening fluid, a rockable conduit communicating with the fountain, a dampening roller mounted for rotation on the conduit, the conduit having outlet apertures formed therein at points located within the roller, driven means for imparting rocking movement to the conduit whereby the said outlet apertures are moved relative to the fluid level in the conduit to discharge fluid from the conduit into the roller, and means for permitting the passage of fluid from the interior of the roller to its exterior.

9. In a dampening device for printing machines, a fountain for dampening fluid, a rockable conduit communicating with the fountain, a dampening roller mounted for rotation on the conduit, the conduit having outlet apertures formed therein at points located within the roller, driven means for imparting rocking movement of variable amplitude to the conduit whereby the said outlet apertures are moved relative to the fluid level in the conduit to discharge fluid from the conduit into the roller, and means for permitting the passage of fluid from the interior of the roller to its exterior.

fluid level in the conduit to discharge variable quantities of fluid from the conduit into the roller, and means for permitting the passage of fluid from the interior of the roller to its exterior.

10. In a dampening device for printing machines, a frame having an aperture formed therein, a fountain for dampening fluid supported by the frame, a conduit supported for rocking movement by the frame and communicating with the fountain through the frame aperture, a dampening roller mounted for rotation on the conduit, the conduit having outlet apertures formed therein at points located within the roller, driven means for imparting rocking movement to the conduit whereby the said outlet apertures are moved relative to the fluid level in the conduit to discharge fluid from the conduit into the roller, and means for permitting the passage of fluid from the interior of the roller to its exterior.

11. In a dampening device for printing machines, a frame having an aperture formed therein, a fountain for dampening fluid supported by the frame, a conduit supported for rocking movement by the frame and communicating with the fountain through the frame aperture, a dampening roller mounted for rotation on the conduit, the conduit having outlet apertures formed therein at points located within the roller, driven means for imparting rocking movement of variable amplitude to the conduit whereby the said outlet apertures are moved relative to the fluid level in the conduit to discharge variable quantities of fluid from the conduit into the roller, and means for permitting the passage of fluid from the interior of the roller to its exterior.

12. In a dampening device for printing machines, a frame having an aperture formed therein, a fountain for dampening fluid supported by the frame, means for maintaining constant fluid level in the fountain, a conduit supported for rocking movement by the frame and communicating with the fountain through the frame aperture, a dampening roller mounted for rotation, the conduit having apertures formed therein at different axial points, driven means for imparting rocking movement of variable amplitude to the conduit thereby moving the apertures from points above the fluid level to points below the fluid level to discharge variable quantities of fluid from the conduit to the roller.

13. In a dampening device for printing machines, a fountain, a reservoir for dampening fluid, means for controlling the flow of fluid from the reservoir into the fountain whereby a constant fluid level is maintained in the fountain, a dampening roller mounted for rotation, a rockable conduit having apertures formed therein at points within the roller, the conduit extending axially through the roller and communicating with the fountain to convey fluid from the fountain into the roller, driven means for rocking the conduit thereby moving its apertures from a point

above the fluid level to a point below the fluid level to thereby discharge fluid from the conduit into the roller, and means for permitting the passage of fluid from the interior of the roller to its exterior.

14. In a dampening device for printing machines, a fountain, a reservoir for dampening fluid, a valve controlling communication between the fountain and the reservoir, a float actuated member operably positioned in the fountain to control the flow of fluid from the reservoir into the fountain to maintain a constant fluid level in the fountain, a dampening roller mounted for rotation, a rockable conduit having apertures formed therein at points within the roller, the conduit extending axially through the roller and communicating with the fountain to convey fluid from the fountain into the roller, driven means for rocking the conduit to move its apertures from a point above the fluid level to a point below the fluid level to thereby discharge fluid from the conduit into the roller, and means for permitting the passage of fluid from the interior of the roller to its exterior.

15. In a dampening device for printing machines, a fountain for dampening fluid, means for maintaining a constant fluid level in the fountain, a dampening roller mounted for rotation, a rockable conduit extending from the fountain and having apertures formed therein, the conduit communicating with the fountain to convey fluid from the fountain to the roller, drive imparting means interposed between a driven component of the printing machine and the conduit for imparting rocking movement to the conduit thereby discharging fluid from the conduit to the roller, and manually controlled means for varying the amplitude of rocking movement imparted to the conduit thereby varying the quantity of fluid discharged from the conduit to the roller.

16. In a dampening device for printing machines, a fountain for dampening fluid, means for maintaining a constant fluid level in the fountain, a dampening roller mounted for rotation, a rockable conduit extending axially through the roller and having apertures formed therein, the conduit communicating with the fountain to convey fluid from the fountain into the roller, a fulcrum, a lever movable about the fulcrum, means for operably connecting the lever to a driven component of the machine to thereby move the lever about the fulcrum, means for operably connecting the lever with the rockable conduit to thereby rock the conduit to discharge fluid from the conduit into the roller, and manually controlled means for varying the amplitude of movement imparted by the lever to the rockable conduit thereby varying the quantity of fluid discharged from the conduit into the roller, and means for permitting the passage of fluid from the interior of the roller to its exterior.

ANTON STOBB.
